COMBINED MOTION PICTURE PROJECTOR AND SUPPORT STAND

Charles Ajar, 4265 Clybourn, North Hollywood,
Calif. 91602

Filed Oct. 6, 1969, Ser. No. 19,426

Term of patent 14 years

Int. Cl. D16—04

U.S. Cl. D61—1

Fig. 1

Fig. 2

Fig. 3

Fig. 4

Fig 5

FIG. 1 is a side elevational view of a combined motion picture projector and support stand in accordance with the present invention;

FIG. 2 is a front elevational view thereof;

FIG. 3 is a rear elevational view thereof;

FIG. 4 is the opposite side elevational view thereof; and

FIG. 5 is an elevational view of another embodiment of FIG. 1 wherein the projector is provided with a more rectangular configuration in its portion above the switch housing portion thereof and unconnected to the switch housing portion, and the switches are located atop the switch housing portion rather than along the side thereof.

I claim:

The ornamental design for a combined motion picture projector and support stand, as shown and described.
